BURKE H. BRIDGERS, OF WILMINGTON, NORTH CAROLINA

GAME APPARATUS

Application filed April 10, 1930. Serial No. 443,145.

This invention relates to game apparatus and its aim is to provide a fascinating and instructive source of pleasure and amusement based on a story of the action of bootleggers and law enforcement officers.

The more specific objects and advantages will become apparent from a consideration of the description following taken in connection with the accompanying drawing illustrating an operative embodiment.

In said drawing:—

Figure 1 is a plan view of the game board;

Figure 2 is a plan view of the boat game piece;

Figure 3 are elevations of game pieces representing law enforcement officers;

Figure 4 are elevations of game pieces representing bootleggers;

Figure 5 are elevations of game pieces representing liquor containers;

Figure 6 are perspective views of stoppers for said containers; and

Figure 7 is a hiding device for one of the jugs or containers.

Referring specifically to the drawing and first to the game board, which may consist of a piece of cardboard or be of any structure desired and have a river represented thereon as at 10, one bank thereof being shown at 11 and the opposite bank at 12. Each bank has a landing as at 13 and 14, the landing 14 being concealed from the opposite shore.

Figure 2 represents a boat adapted for movement in the river 10 and it is of a size to carry one of the men of Figures 3 and 4 and two of the containers of Figure 5 or two of said men.

The men of Figure 3 representing law enforcement officers are decorated in such manner that they are different from each other and so that one will represent a chief enforcement officer and the other two represent lieutenants.

As to the men or game pieces of Figure 4 representing bootleggers, each will be different in appearance and one will represent a boss or head bootlegger and the others lieutenants or assistants.

As to the receptacles or jugs shown in Figure 5, designated 15, 16 and 17, respectively,

they are identical in appearance except that they have removable stoppers as at 18, 19 and 20, bearing the words Scotch, Rye and Corn, respectively.

Figure 7 shows a hollow log or hiding member 21.

The law enforcement officers of Figure 3 are designated 22 for the chief, and 22^a and 22^b for his first and second lieutenants, the bootleggers of Figure 4 are designated 23, one of which may be considered the boss, and the row boat of Figure 2, 24.

The game or puzzle is played or worked by manipulating the boat, the various figures, and the jugs in accordance with the following story, and in such manner that at no time are any of the bootleggers found on the same side of the river with a greater number of officers, the boat upon reaching land being classed as part of the shore on which it has landed. The story follows:

Three bootleggers while transporting their wares, the jugs of three varieties of liquor, are blocked by the river 10. They discover a small boat 24 at the landing 14, the landing 75 being concealed from the opposite side of the river where is located a landing 13. As heretofore stated, the boat is of such a size that only two of the men, or one man and two jugs can be transported at a time. Near the landing 80 is also a hiding place for a single jug indicated by the hollow log 21. Before they can secrete a jug and begin crossing the river they are apprehended by three prohibition officers.

Both parties are heavily armed and are evenly matched. After a parley it develops that the enforcement officers desire also to cross the river, and that all the men except the two junior officers, 22^a and 22^b, can row. 90 The chief officer 22, noting the size of the boat, and realizing that the bootleggers must separate, considers that, as at sometime during the process of crossing the officers will find themselves with a smaller number of 95 bootleggers, an easy capture may be effected. He therefore agrees to do his share of the rowing and to follow without protest any plan of crossing that the boss bootlegger may suggest, but stipulates that he will not trans- 100

fer any of the whiskey. The bootleggers agree that none of them will rebel or attempt to escape.

The chief officer tells the boss bootlegger, 5 in a preliminary parley that neither of his lieutenants will touch liquor in the presence of witnesses, but that, when alone, his first lieutenant 22^a will indulge in Rye or Corn liquor, while the other lieutenant 22^b is part 10 tial to either Corn or Scotch. As the chief officer indicates an interest in the jug of Scotch the boss bootlegger correctly surmises that he also has a weakness and determines not to give him an opportunity at the Scotch 15 even in the presence of his own lieutenants.

The bootleggers obviously cannot conceal any of the jugs in the presence of any of the officers, but may of course transfer them across the river.

20 The puzzle is solved by executing the various moves in accordance with the foregoing conditions, in the least possible number of crossings, with the labor of rowing as evenly divided as possible, bearing in mind the conditions set forth in the story that neither of the junior officers can row, and that the chief officer will not transport any of the whiskey.

It can be played as a game, by one side representing the bootleggers, the other the officers. The bootleggers determine the order and method of play, and a system of scoring is adopted whereby the bootleggers are charged with a point for each crossing, with added penalties for false moves, if detected, 35 and further penalties for the return of men or whiskey captured by the other side. When the crossing has been completed, the score is totaled. The other side then tries, and the lesser score wins.

40 One way of solving the puzzle involved herein is as follows: (First move) The chief officer takes over the second lieutenant and brings the empty boat back. (Second move) The boss bootlegger takes over the jug marked Rye, and brings empty boat back. (Third move) The chief officer takes over the first lieutenant and brings empty boat back. While the officers are on the other side of the river, the boss bootlegger swaps the 45 corks which are the only distinguishing marks between the jugs of Scotch and Corn and puts the Scotch in a secret hiding place. (Fourth move) The third bootlegger takes over the second bootlegger and brings the 50 second lieutenant back. (Fifth move) The boss bootlegger takes over the chief officer and the second bootlegger brings the first lieutenant back. (Sixth move) The second bootlegger takes over the third bootlegger 55 and the chief officer brings empty boat back. (Seventh move) The chief officer takes over the second lieutenant and the boss bootlegger brings the empty boat back. (Eighth move) The boss bootlegger takes over the jugs of 60 Scotch and Corn and the third bootlegger

brings the empty boat back. (Ninth move) The third bootlegger takes over the first lieutenant.

The game or puzzle, may be simplified by agreeing that the first lieutenant will drink 70 only Rye, and the second lieutenant will drink only Corn, or it may be complicated by decreasing the number of bootleggers who can row.

It will be apparent that the selection of 75 prohibition enforcement officers, bootleggers and liquors, the boat and a hollow log are arbitrary. It will be understood, therefore, that any other game pieces may be substituted as may be found desirable, and the 80 locale indicated by the game board changed to conform, without altering the spirit and scope of the invention provided such changes fall within the scope of the claim.

I claim as my invention:—

Game apparatus comprising a game piece 85 to represent a row boat, a set of game pieces representing law enforcement officers, a second set of game pieces representing bootleggers, a third set of game pieces representing containers for liquor, said game pieces of each set the same in number and being selectively applicable to the boat, the pieces of the first and second mentioned sets of game pieces being individually distinguished 90 from each other in appearance and the third mentioned set of game pieces having interchangeable identifying means, the boat having a capacity to convey two of the pieces of the first and second mentioned sets or one 95 piece of either set with two of the pieces of the third set, in combination with a game board having a representation of a body of water adapted to be traversed by the boat.

In testimony whereof I affix my signature. 100
BURKE H. BRIDGERS.
